UNITED STATES PATENT OFFICE.

ROBERT A. LIPSCOMB, OF HOLT, ALABAMA.

MIXING VALVE.

Application filed June 27, 1921. Serial No. 480,883.

To all whom it may concern:

Be it known that I, ROBERT A. LIPSCOMB, a citizen of the United States of America, residing at Holt, in the county of Tuscaloosa and State of Alabama, have invented certain new and useful Improvements in Mixing Valves, of which the following is a specification.

My invention relates to mixing valves for the burning of gas and is more particularly concerned in the production of a movable valve which will not only effect an intimate and perfect mixture of air and gas but which will control and regulate, by its adjustment, the proportions of both elements.

One object of my invention is to provide the burner with a single hollow valve movable relatively to both the air and gas inlet ports to simultaneously control the opening of both.

A further object of my invention is to design the valve as to permit the introduction of the air through the valve while the gas is admitted about the valve and flow with an ejector effect around the air supply port of the valve to induce the inflow of air.

A further object of my invention is to improve the design of the valve as adapted for use with boilers, and to this end the valve is provided with a substantially cylindrical body which merges at one end into an elongated and restricted tapered discharge nozzle which itself constitutes both the air supply port and the gas valve while at its other end the body portion is left open for co-operation with an adjustable cone to regulate the volume of air admitted.

My invention further comprises the novel details of construction and arrangements of parts, which in their preferred embodiment only are illustrated in the accompanying drawings, which form a part of this specification, and in which:

Fig. 1 is a front view of the complete burner.

Fig. 2 is a vertical cross sectional view taken on the line 2—2 of Fig. 1 with the valve and its attached parts shown in side elevation.

Fig. 3 is a horizontal cross sectional view taken on the line 3—3 of Fig. 2 with the valve details shown partly in plan and partly broken away.

Fig. 4 is an end view of the valve.

Figs. 5 and 6 are cross sectional views taken respectively on the lines 5—5 and 6—6 of Fig. 4.

Similar reference numerals refer to similar parts throughout the drawings.

I have illustrated my invention as applied to a mixing valve suitable for burning gas under boilers, but it is to be understood that its size and detailed structure may be widely varied as applied to different uses.

In the embodiment illustrated, I show the gas supply delivered through a pipe 1 past the present well known type of slide valve 2 into the valve casing 3 which has a right angled burner nozzle 4 adapted to enter the boiler or combustion chamber typically indicated at 24. Across the inner end of the passage through this nozzle 4 is a transverse partition 5 having a taper valve seat 6 therein facing toward the combustion chamber. The casing is divided into half sections on a horizontal plane extending centrally through the valve seat 6 and the casing sections are provided with flanges 7 which are bolted together after the valve, which will now be described, is assembled in the casing.

It will be observed, by reference to Fig. 3, that the type of valve which I consider preferable for my purposes is of the wide thin type to the end that a wide spread distribution of the combustible mixture will result. As shown the valve is formed of two body portions 8 and 9, one being an outer cylindrical sleeve or body 8 and the other being a hollow flaring nozzle 9 which is gradually flattened from a circular inner end 9^a that receives and is connected to the sleeve 8. The outer end of the nozzle is enlarged for its full width and reversely tapered to form by its outer side a valve face 10 and by its inner side an elongated narrow tapering air supply port or nozzle 11, which extends the full width of the valve, as is more clearly indicated in Figs. 4 and 6. At each end on its under face the tapered inner end of the valve is provided with legs or supports 12 which rest on the underside of the casing nozzle 4 and slide thereon as the valve is adjusted through-out its operating positions, thereby preventing any tendency of the wide valve to tilt or cock.

The tubular valve body 8 passes through

2

a central opening 13 in the outer wall of the valve casing 3, there being a suitable stuffing box 14 and gland 15 to provide a tight packing about the body while leaving it free to slide in and out therethrough. The outer end of the body is left open and I attach to any suitable support such as the pipe 1 an angled bracket 16, which, at its lower end in line with the axis 10 of the cylindrical body 8, is provided with a threaded opening for the reception of a screw shank 17 carrying an air control cone 18, which is adjustable towards and adapted by the extent to which it enters the open 15 end of body 8 to control the cross sectional area of the air admission opening to the hollow valve. At one side of the casing 3 I attach lugs 19 to which I pivot a valve opening lever 20. This lever at its center 20 is provided with an annular band 21 which loosely surrounds the valve body 8 and is connected thereto by having elongated slots 22 in the ring receive pins 23 on the sleeve. By grasping the free end of the lever 20, 25 the valve as a whole can be adjusted axially with relation to its gas inlet valve seat 6 and the air inlet control cone 18 to thereby jointly and simultaneously control the admission of air and gas through the valve 30 casing nozzle 4 to the boiler furnace. The air admitted through the body 8 is distributed by the flattened tubular valve and discharged ultimately through the air supply nozzle 11, its volume being jointly controlled by the ejector action of the gas flowing about the nozzle 11 and by the relative adjustment of the cone 18 to the air intake end of the valve. When the cone 18 has been properly adjusted to admit the requisite volume of air for the gas, the joint control of both air and gas is attained merely by the axial adjustment of the valve. As the valve is moved outwardly from the furnace 24 the volume of air and gas are 40 gradually reduced and as it is moved inwardly their volume is gradually increased, but always in their predetermined relative proportions. If it be desired to vary the volume of air admitted, this can be 45 accomplished by an independent adjustment of the cone 18 after the valve is set to its working position, thus increasing the flexibility of the control without at the same time disturbing the joint control of the two 50 elements.

My invention in its broad sense is applicable to mixing valves of varying types according to the duty required and is not intended to be restricted to the specific type 55 of valve disclosed.

Having thus described my invention, what I claim as new and desire to secure by Letters Patent, is:—

1. A mixing valve mechanism comprising 65 a valve casing connected to a source of gas

supply and having a gas outlet port and opposite thereto an opening, a valve movable in the casing and adapted to close said port and to project through said opening, there being an air conduit leading from the 70 exposed outer end of said valve and opening through its inner end opposite said port, and means to regulate the volume of air admitted through the open outer end of the valve.

2. A mixing valve mechanism comprising 75 a valve casing connected to a source of gas supply and having a gas outlet port and opposite thereto an opening, a valve movable in the casing and adapted to close said port and to project through said opening, 80 means to move the valve to open and close said port and regulate its intake of air, and packing to prevent the access of air to the casing about the outer end of the valve.

3. In a mixing valve mechanism, a gas 85 supply casing having an inner transverse partition provided with a gas port, a hollow valve open at both ends which projects through said port and is enlarged to seat against and close said port when moved outwardly, said valve having its outer end projecting through and without said casing, a packing about said end, means to adjust the valve, and means to vary the admission of air to the open outer end of said hollow 95 valve.

4. In a mixing valve mechanism, a chamber supplied with gas and having a transverse partition formed with a gas port, a hollow valve open at its inner end which is 100 adapted to project through said port and when moved outwardly to close said port, said valve having communication with a cylindrical outer end which projects through the valve casing, a packing gland surrounding said cylindrical end, and a cone supported independently of the valve and adapted to enter the outer end of its cylindrical portion. 105

5. In a gas burner, a gas supply chamber 110 having a partition formed with a gas port, a hollow gas valve having its inner end passing through said port and reversely tapered to form on its outwardly facing side a valve seat and on its inwardly facing end a tapering air supply nozzle, said valve having a tubular body portion adapted to project without the casing, a packing gland surrounding said tubular portion, a fixed bracket, a cone adjustably mounted 115 thereon opposite the open end of the valve body, and means to reciprocate the valve, substantially as described.

6. In combination, a gas supply chamber 120 having a transversely elongated burner nozzle with a partition therein formed with an elongated narrow gas port, said casing being divided into half sections through said port, a hollow valve having a reversely tapered end which forms an elongated nar- 130

row air supply nozzle at its inner end and which is adapted when moved outwardly to seat against and close said gas port, said valve being shaped to merge into a cylindrical outer end portion, a stuffing box in the gas chamber through which said cylindrical end portion of the valve projects, a fixed bracket having an adjustable cone adapted to enter the outer open end of said cylindrical portion of the valve, and means to adjust the valve axially to regulate both air and gas.

7. In a mixing valve, a valve chamber having gas inlet and outlet ports, a valve projecting through said outlet port and movable against the direction of flow of the gas stream to close said port, there being an air supply passage opening through the inner end of said valve, and an air regulator 20 towards which the valve is movable in reducing the flow of gas and which is adapted

to throttle the inflow of air proportionate with the gas.

8. In a mixing valve, a valve chamber having gas inlet and outlet ports, a valve 25 having an air duct therethrough and an air nozzle at its inner end, said inner nozzle end of the valve being adapted to project through and by an outward movement to control said gas outlet port with the air 30 nozzle surrounded by the inflowing gas so as to induce by an injector action the inflow of air at the center of the entering gas, and a regulating cone disposed to enter the open outer end of said air duct and adapted to 35 regulate the volumetric flow of air proportionately with the gas.

In testimony whereof I affix my signature.

ROBERT A. LIPSCOMB.
